UNITED STATES PATENT OFFICE.

WALTER D. BUTZ, OF NORRISTOWN, PENNSYLVANIA.

DESIGN FOR AN ARTICLE OF HOSIERY.

No. 40,066.

Specification for Design.

Patented June 15, 1909.

Application filed March 15, 1909. Serial No. 483,653. Term of patent 14 years.

To all whom it may concern:

Be it known that I, WALTER D. BUTZ, a citizen of the United States, residing in Norristown, Pennsylvania, have invented a new, original, and ornamental Design for Hosiery, of which the following is a specification.

The figure in the accompanying drawing shows a side view of an article of hosiery showing my new design.

The distinctive feature of the design is the ornamental band a located at the junction of the ribbed top b with the leg c.

I claim:

The ornamental design for an article of hosiery, as shown.

WALTER D. BUTZ.
